UNITED STATES PATENT OFFICE

2,255,512

REFRIGERANT EVAPORATOR

Delbert F. Newman, Schenectady, N. Y., assignor
to General Electric Company, a corporation of
New York

Application November 1, 1939, Serial No. 302,376

2 Claims. (Cl. 62—126)

My invention relates to refrigerant evaporators, and particularly to evaporators of the flooded type constructed from sheet metal.

Evaporators for household refrigerating machines are commonly constructed of sheet metal, a double wall structure being provided by bending a single sheet on itself or by securing separate sheets together and providing suitable indentations between the wall portions to form the required refrigerant passages. When metals of high thermal conductivity, such as copper, copper alloys, or aluminum, are employed, the thickness of the sheets makes little difference in the efficiency of the evaporator. However, when it is desired to construct an evaporator of other metals, such as stainless steel, which have relatively low coefficients of thermal conductivity, it becomes desirable to employ much thinner sheets in order to reduce the thickness of metal through which the heat is to be transferred from the medium to be cooled to the refrigerant. The thickness of material which may be employed is, of course, limited by the pressure to be maintained in the evaporator as it is desirable to avoid any deformation of the evaporator surface due to pressure. Such deformation is a particular disadvantage in evaporators having shelves for supporting freezing trays and the like since it is essential that as great a portion of the refrigerant conduit surface as possible be maintained flat and be available to contact the surface of the freezing tray. If the surface of the shelf adjacent the refrigerant conduits should become bulged due to pressure in the evaporator, the effective heat conducting area in the shelf will be greatly reduced. Accordingly, it is an object of my invention to provide a refrigerant evaporator which may be constructed of thin sheet metal and which will effectively resist deformation due to pressure within the refrigerant passages thereof.

Another object of my invention is to provide an evaporator of the flooded type constructed of sheet metal and having a header formed in a plurality of sections so arranged as to effectively prevent deformation of the evaporator surface due to pressure of the refrigerant therein.

Further objects and advantages of my invention will become apparent as the following description proceeds, and the features of novelty which characterize my invention will be pointed out with particularity in the claims annexed to and forming a part of this specification.

For a better understanding of my invention, reference may be had to the accompanying draw-

ing in which Fig. 1 is a perspective view of an evaporator embodying my invention; Fig. 2 is a front elevation view of the evaporator shown in Fig. 1; Fig. 3 is an enlarged sectional view on the line 3—3 of Fig. 2; Fig. 4 is an enlarged sectional view on the line 4—4 of Fig. 2; and Fig. 5 is a plan view of the double wall structure of the evaporator shown in Fig. 1 before bending.

Referring now to the drawing, in Figs. 1 and 2, I have shown a flooded evaporator of the type employed in household refrigerating machines and comprising a double walled structure of b-shaped cross-section providing vertical walls 10 and 11 and horizontal freezing tray supporting shelves 12 and 13, the wall 13 having a flange 14 welded or otherwise secured to the wall 10 and forming with the other walls a lower freezing chamber 15. A sheet metal wall 16 is secured to the top of the vertical wall 11 and, together with the upper portion of the wall 10, provides an upper freezing chamber 17. The upper ends of the walls 10 and 16 are provided with horizontal flanges 18 and 19 respectively which are adapted to be secured to the top wall of the refrigerator cabinet liner, holes 20 and 21 being provided in the flanges 18 and 19 for this purpose. The double wall portion of the evaporator is constructed from inner and outer complementary sheet metal portions 22 and 23 respectively, as indicated in Figs. 3 and 4. In constructing the double wall portion, the sheets 22 and 23 while flat are stamped with suitable indentations to form the necessary refrigerant header and circulating refrigerant passages and are then secured together in face engagement while flat, as shown in Fig. 5, the sheet 23 being shown on the top. The sheets 22 and 23 are provided with parallel semi-cylindrical indentations near one end thereof which cooperate to provide two cylinders 24 and 25 connected by passages 26 at their ends and constituting a header for the separation of liquid and gaseous refrigerant. A portion of the sheets 22 and 23 forming a strip of wall 27 between the cylinders 24 and 25 are securely welded or otherwise suitably bonded together. The sheets 22 and 23 are provided with U-shaped indentations 28 and 29 respectively, which form refrigerant circulating passages communicating with and depending from the lower cylinder 25 of the header. The passages 28 and 29 extend from the header through the wall 10 and across the freezing shelf 12. A sinuous conduit is formed in the walls 11 and 13 by indentations 30 and 31 in the walls 22 and 23 respectively, and terminates in a manifold 32 formed by indenta-

tions in the outer sheet 23. A plurality of refrigerant injecting ducts 33 are provided to convey refrigerant from the manifold 32 to the lower portions of the U-shaped refrigerant passages formed by the indentations 28 and 29. The flat double wall structure shown in Fig. 5 is bent along the dotted lines after the sheets have been welded along their edges and between the indentations to provide the b-shaped structure shown in Figs. 1 and 2, and the flange 14 is welded or otherwise suitably secured to the wall 10. The sheet metal wall 16 is then welded or otherwise suitably secured to the wall 11 to enclose the upper freezing chamber.

A liquid line 34 is provided to admit refrigerant to the evaporator and communicates through a passage 35 with the sinuous conduit formed in the walls 12 and 13. Refrigerant vaporized in the evaporator is removed through a suction line 36 arranged to conduct the vapor from the upper cylinder 24 of the header.

The cylinders 24 and 25 and the connections 26 form a header of sufficient volume to provide for a proper separation of liquid and gaseous refrigerant and to maintain the U-shaped passages flooded with liquid refrigerant at all times. By providing the two relatively small parallel cylinders instead of a single header, less pressure is exerted along the walls where the sheets 22 and 23 are jointed around the header and between the cylinders and a thinner gauge sheet metal may be employed to construct a header of this type than would be possible with a single header. The U-shaped indentations 29 in the outer sheet 23 are of rounded cross-section and effectively resist deformation due to pressure. It is essential, however, that a flat surface be provided in the upper portion of the shelf 12 and it is, therefore, impossible to employ a rounded indentation. When the evaporator is constructed of thin metal, pressures may be sufficient to cause a bulging of the upper surface of the shelf if it is not provided with indentations. However, I have found that by constructing the indentations 28 so that they have trapezoidal cross-section, deformation of the shelf area due to pressure is effectively avoided since the trapezoidal cross-section reduces the length of straight cross-section against which the pressure acts. In this manner, a refrigerant conduit or passage is provided which is of sufficient size to carry the required quantity of refrigerant and provides the flat surface necessary for contact with freezing trays and the like. It has been found desirable to form the sinuous conduit in the walls 11 and 13 so that it has a smaller cross-sectional area than the U-shaped passages in the other walls, and I, therefore, have illustrated the indentations 30 and 31 as having trapezoidal cross-sections. The conduits 31 and the shelf 13, therefore, present a flat surface of substantial area in contact with the freezing trays and deformation of the walls of the indentations in both the inner and outer sheet metal portions is prevented.

By constructing the header of two cylindrical portions and by providing the indentations of

10 trapezoidal cross-section particularly in the shelf areas, it is possible to construct an evaporator of thin sheet metal of relatively low conductivity which will effectively resist deformation due to pressure and also effectively increase the capacity of the evaporator because of the reduced thermal resistance of the walls thereof.

15 While I have described my invention in connection with an evaporator for household refrigerators, I do not desire my invention to be limited to the particular construction shown and described, and I intend in the appended claims to cover all modifications within the spirit and scope of my invention.

20 What I claim as new and desire to secure by Letters Patent of the United States is:

25 1. An evaporator of the flooded type for refrigerating machines comprising complementary sheet metal portions secured together in face engagement and formed to provide at least one vertical wall, said sheet metal portions having indentations therein near the top of said vertical wall forming two parallel horizontally extending substantially identical cylinders of relatively small diameter and passages connecting said cylinders at their ends to constitute said cylinders a liquid and vapor separating header, said sheet metal portions being securely bonded together between said indentations, at least one of said sheet metal portions having a plurality of parallel indentations formed therein to provide refrigerant passages communicating with and depending from the lower one of said cylinders, means for admitting liquid refrigerant to said passages, and means for conducting vaporized refrigerant from the upper one of said cylinders.

30 2. An evaporator of the flooded type for refrigerating machines comprising complementary sheet metal portions secured together in face engagement and formed to provide at least one vertical wall and a freezing shelf, said sheet metal portions having indentations therein near the top of said vertical wall forming two parallel horizontally extending substantially identical cylinders and passages connecting said cylinders at their ends to constitute said cylinders a liquid and vapor separating header, said sheet metal portions being securely bonded together between said indentations, said sheet metal portions having a plurality of complementary indentations formed therein to provide refrigerant circulating passages communicating with said header, the indentations in the sheet metal portion forming the bottom surface of said shelf being of rounded cross-section and the complementary indentations formed in the upper surface of said shelf being of substantially trapezoidal cross-section whereby a flat surface is provided along said refrigerant passages in said shelf and said indentations are adapted to resist relatively high pressures without deformation, means for admitting liquid refrigerant to said passages, and means for conducting vaporized refrigerant from the upper one of said cylinders.
